(57) **CLAIM**

The ornamental design for a facial portion of an orthodontic appliance, as shown and described.

DESCRIPTION

FIG. 1 is a bottom, front, left side perspective view of a facial portion of an orthodontic appliance showing our new design;

FIG. 2 is a top, rear, left side perspective view thereof;

FIG. 3 is a left side elevational view thereof;

FIG. 4 is a right side elevational view thereof;

FIG. 5 is a top plan view thereof;

FIG. 6 is a bottom view thereof;

FIG. 7 is a front elevational view thereof;

FIG. 8 is a rear elevational view thereof;

FIG. 9 is a bottom, front, left side perspective view of a facial portion of an orthodontic appliance illustrating another embodiment of our new design;

FIG. 10 is a top, rear, left side perspective view thereof;

FIG. 11 is a left side elevational view thereof;

FIG. 12 is a right side elevational view thereof;

FIG. 13 is a top plan view thereof;

FIG. 14 is a bottom view thereof;

FIG. 15 is a front elevational view thereof; and,

FIG. 16 is a rear elevational view thereof.

The broken line drawings of a base and of an archwire slot liner are for illustrative purposes only and form no part of the claimed design.
